UNITED STATES PATENT OFFICE.

WILLIAM P. KELLOGG, OF TROY, NEW YORK.

TRACE-CARRIER.

SPECIFICATION forming part of Letters Patent No. 606,347, dated June 28, 1898.

Application filed March 26, 1897. Renewed May 11, 1898. Serial No. 680,419. (No model.)

To all whom it may concern:

Be it known that I, WILLIAM P. KELLOGG, a citizen of the United States, residing at Troy, county of Rensselaer, and State of New York, have invented certain new and useful Improvements in Back-Band Buckles, of which the following is a specification.

The invention relates to such improvements; and it consists of the novel construction and combination of parts hereinafter described and subsequently claimed.

Reference may be had to the accompanying drawings, and the letters of reference marked thereon, which form a part of this specification.

Similar letters refer to similar parts in the several figures.

Figure 1 of the drawings is a front elevation of my improved buckle unattached and showing part of a trace-chain in a supported position. Fig. 2 is a side or edge view of the same. Fig. 3 is a similar view showing my invention in a modified form.

My invention comprises an improvement upon that well-known form of back-band buckle which has a web-plate A, provided with parallel cross-slots A' and A'', adapted to receive the webbing, and with a hook B, adapted to enter one of the links B' of a trace-chain and support the trace, also having a wedge-plate C, provided with end journals C', having bearings in the ears A³ and A⁴ on the web-plate, all constructed in the usual well-known manner.

My improvement relates to means for locking the trace-chain within the hook B. Various devices have been heretofore devised for this purpose, and it would seem to be a very difficult as well as important matter.

My improvement consists in making the lower side edges C² of the wedge-plate and the upper end B² of the hook approximately meet and in projecting the middle portion of the wedge-plate down considerably below the horizontally-extended edges C² and the hook end B² in the form of a tongue D, which overlies and laps the hook, as shown. This form of construction makes a perfect lock, is easily constructed, cheap, and durable, and presents

a symmetrical and ornamental appearance.

As the trace-chain is rattled about in use the link containing the hook slips up on the

hook and tends to open the wedge-plate; but the link must pass the lower end of tongue D before it can engage the main plate to communicate an opening tendency, and after it passes such lower end it incloses both the tongue and hook, as indicated by dotted lines in Fig. 2, thereby holding the wedge-plate in a closed position. Before the link can slide above the upper end B² of the hook it engages the lower plate edges C², which prevent the link from assuming any position near the upper part of the hook in which it will not positively lock the hook and tongue together, so that the link cannot escape from the hook; but it is essential that the lower edges of the wedge-plate should be provided with some kind of stop which will prevent the link from slipping up the tongue past the upper end of the hook.

In Fig. 2 I have shown the lower edges laterally extended on opposite sides of the tongue approximately in horizontal line with the upper end of the hook.

In Fig. 3 I have shown the wedge-plate tongue bent inwardly to form the wedging-bevel D', which will serve to bind the tongue and hook together when the trace-link rises, as shown in Fig. 3, so tightly that the wedge-plate is wholly incapable of movement relatively to the web-plate, thereby preventing the wear upon the webbing caused by frequent though slight movements of the wedge-plate and the web-engaging teeth located on such plate.

I am aware that various forms of construction have been proposed which include a stop across the mouth of the hook, usually to be formed by bending a lower part of the wedge-plate into a position at right angles to the body of the plate, and I do not claim any such form of construction. The plate being of comparatively thick sheet metal is materially weakened when bent at right angles and the bent portion is easily broken off.

By making the buckle as shown in Fig. 3 of my drawings the lower edges of the body part of the plate, being in line with the top of the hook, form, without any bending, a sufficient stop to prevent the escape of the chain from the hook.

By giving a slight bend or inclination to the overlapping tongue, as shown in Fig. 3, I pro-

vide a stop which not only prevents the escape of the chain from the hook, but also any vibratory opening-and-closing movement of the wedge-plate to wear the webbing.

5 If the lapping tongue passed down on one or both sides of the hook, as has been proposed, instead of over or outside of the hook, the jerky movements of the link would cause the link to directly engage the side lapping parts and produce the vibratory opening-and-closing movements of the tongue and plate above referred to.

What I claim as new, and desire to secure by Letters Patent, is—

15 1. In a back-band buckle, the combination with the web-plate provided with parallel web-slots and journal-bearings, of an upwardly-turned trace-hook depending from the lower side of the web-plate, a wedge-plate
20 journaled in the web-plate, a tongue comprising a downward extension of the wedge-plate

overlapping the hook, and a stop outside the mouth of the hook for locking a chain-link upon the hook, substantially as described.

2. In a back-band buckle, the combination ²⁵ with the web-plate, and upwardly-turned hook depending from its lower edge, of a wedge-plate, and a hook-lapping tongue depending from the lower edge of the wedge-plate, inclined outwardly from the outer side ³⁰ of hook to the lower edge of the wedge-plate whereby it forms a stop outside the mouth of the hook for locking a chain upon the hook and the wedge-plate against vibratory opening-and-closing movements, substantially as ³⁵ described.

In testimony whereof I have hereunto set my hand this 23d day of March, 1897.

WM. P. KELLOGG.
